(57) **CLAIM**

The ornamental design for a fuel delivery module, as shown and described.

DESCRIPTION

FIG. 1 is an isometric view of a fuel delivery module in a closed position;

FIG. 2 is another isometric view of the fuel delivery module of FIG. 1 in an open position;

FIG. 3 is another isometric view of the fuel delivery module of FIG. 1 in the closed position;

FIG. 4 is front view of the fuel delivery module of FIG. 1 in the closed position;

FIG. 5 is a rear view of the fuel delivery module of FIG. 1 in the closed position;

FIG. 6 is right side view of the fuel delivery module of FIG. 1 in the closed position;

FIG. 7 is left side view of the fuel delivery module of FIG. 1 in the closed position;

FIG. 8 is top view of the fuel delivery module of FIG. 1 in the closed position; and,

FIG. 9 is bottom view of the fuel delivery module of FIG. 1 in the closed position.

The broken lines in the Figures are for illustrative purposes only and form no part of the claimed design.
